US0D1088777S

(12) **United States Design Patent** (10) **Patent No.:** **US D1,088,777 S**
(45) **Date of Patent:** **** Aug. 19, 2025**

(54) **RATCHET**

(71) Applicant: **Harbor Freight Tools USA, Inc.**,
Calabasas, CA (US)

(72) Inventors: **Jordan Greene**, Westerville, OH (US);
Craig Steinfels, Powell, OH (US)

(73) Assignee: **Harbor Freight Tools USA, Inc.**,
Calabasas, CA (US)

(**) Term: **15 Years**

(21) Appl. No.: **29/890,842**

(22) Filed: **Apr. 27, 2023**

(51) LOC (15) Cl. **08-05**

(52) U.S. Cl.

USPC **D8/25**

(58) **Field of Classification Search**

USPC D8/24, 107, 21, 22, 25; D10/83

CPC B25B 23/1425

See application file for complete search history.

(57) **CLAIM**

The ornamental design for a ratchet, as shown and described.

DESCRIPTION

FIG. 1 is a bottom and front perspective view of a ratchet showing our new design;

FIG. 2 is a front elevation view thereof;

FIG. 3 is a rear elevation thereof;

FIG. 4 is a left side elevation view thereof;

FIG. 5 is a right side elevation view thereof;

FIG. 6 is a bottom plan view thereof;

FIG. 7 is a top plan view thereof; and,

FIG. 8 is a bottom and rear perspective view thereof.

The dashed broken lines in the figures illustrate portions of the ratchet that form no part of the claimed design.

1 Claim, 5 Drawing Sheets
